UNITED STATES PATENT OFFICE

2,362,831

ELASTIC FLUID TURBINE

Hans Kraft, Schenectady, N. Y., assignor to General Electric Company, a corporation of New York

Application August 20, 1943, Serial No. 499,369

5 Claims. (Cl. 253—76)

The present invention relates to elastic fluid turbines, more particularly to nozzle and diaphragm arrangements used in the low pressure part of such turbines, in which elastic fluid carries an increasing amount of moisture, such as water, in the case of steam turbines. A substantial part of the water or moisture is deposited on the nozzle partitions. The water flows slowly along the surfaces of the partitions and as it reaches the outlet edges of the partitions it is blown off and forced towards the buckets of the succeeding wheel. Water or like liquid impinging on the entrance edges of such buckets may cause erosion and gradual destruction of the bucket entrance edges with resultant loss in efficiency of the turbine.

The object of my invention is to provide an improved construction and arrangement of elastic fluid turbines whereby the aforementioned difficulties are substantially reduced. This is accomplished by an improved nozzle arrangement with hollow partitions forming slots opening along the surfaces, preferably the exit edges, of the partitions and means for connecting the hollow partitions to a vacuum or a point of lower pressure. The suction thus produced forces the water deposited on the surfaces of the partitions along such surfaces into the slots, whence the water may be carried away to a suitable point, such as the condenser of the turbine or heating system for feed water or the like.

For a better understanding of what I believe to be novel and my invention attention is directed to the following description and the claims appended thereto in connection with the accompanying drawing.

In the accompanying drawing, Fig. 1 illustrates a sectional view, partly broken away, of an elastic fluid turbine embodying my invention; Fig. 2 is an enlarged detail view of Fig. 1; Fig. 3 is a section along line 3—3 of Fig. 2, Fig. 2 being a section along lines 2—2 of Fig. 3; Fig. 4 shows a modification of my invention; Fig. 5 is a section along line 5—5 of Fig. 4; Fig. 6 is another modification of my invention, and Fig. 7 is a section along line 7—7 of Fig. 6.

The turbine comprises a casing 10 with a plurality of axially spaced diaphragms 11 supported on the casing. The diaphragms are cooperatively associated with a rotor including a plurality of bucket wheels 12 secured to a shaft 13. During operation, elastic fluid, such as steam or mercury vapor, is conducted to a diaphragm, whence it is directed into a bucket wheel which in turn discharges into a succeeding diaphragm.

Each diaphragm has an inner disk 14 (Fig. 2) with a plurality of circumferentially spaced partitions 15 secured at their inner ends to the rim of the disk 14. The outer ends of the partitions are secured, preferably welded, to an outer ring

16 held in a groove of the casing 10. The construction so far described is well known in the art.

In order to remove water or the like moisture deposited on or flowing slowly along the surfaces of the partitions the latter are made hollow. In the present example each partition has a radial bore 17 formed within the entrance portion of the partition and a slot 18 extending from the bore 17 through the exit edge portion 19. The slot 18 is curved, conforming substantially to the curvatures of the convex and concave surfaces of the partition. The outer ends of the bore or channel 17 of each partition communicates with a radial bore 20 extending through the ring 16 and leading to an annular groove 21 formed in the casing 10. The groove 21 is connected by a channel 22 to a pipe 23 leading to a condenser 24 for receiving exhaust fluid from the turbine.

20 In Fig. 1 of the drawing I have indicated a channel 22 and a pipe 23 in connection with the first diaphragm 11 only. The annular grooves 21 around the other diaphragms are directly connected to a point of low pressure, in the present instance the exhaust conduit of the turbine, by means of radial channels 22a in the lower part of the turbine casing.

In a preferred embodiment the exit edges of the partitions are cut away on the convex side 30 of the partitions to facilitate the flow of moisture from said convex surfaces into the slots 18 or, from another viewpoint, the wall portion of each partition forming its concave side is extended in the direction of flow of fluid from the nozzles 35 in order to assure substantial draining of moisture from the convex wall portion of the partition into the slot 18.

The modification of my invention as shown in Figs. 4 and 5 has a turbine casing 26. A diaphragm or like nozzle member or section 27 is supported in a groove 28 of the casing 26. The diaphragm has a plurality of circumferentially spaced, hollow partitions 29. These partitions may be made from sheet material by a forming process. The exit portions 30 of the partition walls are spaced to form a slot 31 through which fluid may be conducted from the nozzle passages between the partitions into the hollow spaces within the partitions. The inner ends of the partitions are connected to a disk or like member 32 and the outer ends of the partitions are secured to a channel member which is in the form of a hollow ring 33 forming an annular channel 34 in case the nozzle arrangement forms nozzles 50 over the entire arc of 360°. The hollow channel or ring 33 is seated in the aforementioned groove 28 of the casing 26. The annular channel at the lower portion of the diaphragm has a discharge opening 35 sealed to a discharge channel 36 in 55 the casing wall by means of a connecting sleeve

37. A drain conduit 38 is fused to the casing 28 to receive fluid from the discharge channel 38. The drain conduit 38 is connected to a point of pressure low enough to induce flow of fluid through the slots 31 into the hollow partitions. The hollow space formed within at least some of the partitions communicates with the channel 34 through radial openings 39 in the channel member 33.

During operation, moisture or liquid flowing along the convex and concave surfaces of the partitions is drawn into the slots 31 in the partitions and discharged therefrom through the channel 34, whence the fluid is conducted into the drain conduit 38.

The elastic fluid turbine arrangement of Figs. 6 and 7 comprises a turbine casing 45 and a rotor 46 disposed within the casing and including a row of circumferentially spaced buckets 47 forming bucket passages between them. Elastic fluid is conducted to the bucket passages by a nozzle arrangement which includes a row of circumferentially spaced partitions 48 attached to an outer ring or support, in the present instance directly secured to the casing 45. Each partition has an outer dovetailed base 49 engaging a corresponding dovetailed circumferential recess 50 in the casing 45. The inner ends of the partitions 48 are connected to a shroud or band 51. The partitions are hollow. Each partition has an inner wall 52 (Fig. 7), thus forming two separate chambers, spaces or cavities 53 and 54 connected through slots to the outer surfaces of the partition. The cavity 53 communicates through a slot 55 with the concave surface and the cavity 54 communicates through a slot 56 with the convex surface of the partition. The partition has a sharp exit edge. The slots 55, 56 are spaced from the exit edge. The slot 56 forming an inlet to the cavity 54 is located at a greater distance from the exit edge than the slot 55. Thus, in this arrangement several chambers are formed inside a partition for receiving fluid from different points of the nozzle space. The surfaces of the partition ahead and beyond the slots 55, 56 may form smooth continuations. In some instances, however, it is desirable to assure some scoop action into one of the cavities. Thus, in the present instance an exit portion 57 of the concave blade surface is thickened in order to facilitate flow of fluid into the cavity 53 through the slot 55. This is especially important in case the pressure in the chamber 53 is slightly greater than the pressure outside the partition near the entrance to slot 55. The scoop action causes some of the velocity energy of the fluid to be converted into pressure energy to overcome the slightly greater pressure in the cavity 53. In other instances it may be desirable to reduce the thickness of the blade portion adjacent the slot 56 or to increase the thickness of the blade portion ahead of the slot 55 as regards the direction of flow through the nozzles passage. The two cavities or chambers 53, 54 are connected to separate discharge channels 58, 59 formed in the bottom of the groove or recess 50 and connected by separate conduits 60, 61 to points of consumption such as for example a fluid heating system, not shown.

Having described the method of operation of my invention, together with the apparatus which I now consider to represent the best embodiment thereof, I desire to have it understood that the apparatus shown is only illustrative and that

the invention may be carried out by other means.

What I claim as new and desire to secure by Letters Patent of the United States is:

1. Elastic fluid turbine comprising a casing, a plurality of diaphragms supported in the casing, a rotor having bucket wheels associated with the diaphragms, each diaphragm having a plurality of circumferentially spaced partitions, an outer ring secured to the outer ends of the partitions, and means for removing moisture from the surfaces of the partitions comprising channels formed in the partitions and extending through the exit edges thereof and means to induce a suction in said channels to induce moisture on the partitions to enter said channels.

2. Elastic fluid turbine comprising a casing, a plurality of diaphragms supported on the casing, a rotor having bucket wheels associated with the diaphragms, each diaphragm having a plurality of circumferentially spaced partitions, an outer ring secured to the outer ends of the partitions, each partition forming a slot having an inlet extending through and along the exit edge of the partition, and means for connecting said slots to a point of pressure lower than that normally existing near the exit edge of the partition to drain liquid deposited on and flowing along the surfaces of the partitions.

3. Elastic fluid turbine comprising a casing, a plurality of diaphragms supported on the casing, a rotor having bucket wheels associated with the diaphragms, at least one diaphragm having a plurality of circumferentially spaced partitions, an outer ring secured to the outer ends of the partitions, each partition forming a slot having an inlet extending along the exit edge of the partition, and means including channels formed in the outer ring and the casing for connecting said slots to a point of pressure normally lower than that existing near the exit edges of the respective partitions.

4. Elastic fluid turbine having a casing and a diaphragm supported on the casing and comprising a plurality of circumferentially spaced partitions forming nozzle passages between them, each partition being curved in the direction of flow and being convex on one side and concave on the other, means for removing moisture from the concave and convex surfaces of each partition, said means including a channel formed in each partition and extending through and along the exit edge of the partition, and means for connecting said channel to a point of pressure lower than that normally existing near said exit edge to induce a flow of moisture from said surfaces into said channel, the exit edge on the convex side of each partition being partly cut away to facilitate the flow of fluid from the convex surface into the channel.

5. In an elastic fluid turbine, a casing, a nozzle arrangement for conducting fluid to a bucket wheel disposed in the casing, said arrangement comprising a plurality of circumferentially spaced hollow partitions, each forming a space with an inlet extending through its exit edge, a channel member forming a channel secured to the outer ends of the partition and communicating with the space of at least some of the partitions, and means for connecting said channel to a point of pressure low enough to induce flow of fluid through said slots into the partitions, and means for draining fluid from said channel.

HANS KRAFT.
